UNITED STATES PATENT OFFICE.

PALMER COX, OF NEW YORK, N. Y.

DESIGN FOR A RULER.

SPECIFICATION forming part of Design No. 22,584, dated July 4, 1893.

Application filed May 10, 1893. Serial No. 473,747. Term of patent 14 years.

To all whom it may concern:

Be it known that I, PALMER COX, a citizen of the United States, residing in the city, county, and State of New York, have invented a new and original Design for Rulers, of which the following is a specification, reference being had to the accompanying drawing, forming part thereof.

The design consists in five series of Brownies each of which series may be termed as follows:—"Brownies going to school," "Brownies late," "Brownies very late," "Brownies at school," "Brownies returning from school." They appear on the surface of a ruler as hereinafter described.

In the drawing:—the figure, is a front surface of a ruler on which is shown my design.

The first series, namely, the "Brownies going to school," is composed of the ordinary, Alpine, student, Japanese, Italian, Egyptian, original, ordinary, French, ordinary, Arab and twin brownies.

The second series, namely, the "Brownies late," is composed of the dude, Highland, English, jockey, Indian, Esquimau, Irish, Spanish, principal, Canadian, Scotch and Uncle Sam brownies.

The third series, namely, the "Brownies very late," is composed of the policeman, royal, Turk, sailor, Hollander, German, soldier, twin, Chinese, Russian, original and ordinary brownies.

The fourth series, namely, the "Brownies at school," is composed of the policeman, original, Chinese, royal, twin, soldier, sailor, ordinary, German, Turk, Hollander, Russian and ordinary brownies.

The fifth series, namely, the "Brownies returning from school," is composed of the Scotch, ordinary, Esquimau, German, Hollander, Uncle Sam, Russian, Turk, dude, twin, sailor and Canadian brownies.

The series of brownie characters is intended to give a pleasing effect to a ruler as well as to serve as an incentive to the use of rulers by children.

I claim—

The design for a ruler, substantially as herein shown and described.

PALMER COX.
